(57) **CLAIM**

The ornamental design for a sling with drawstring, as shown and described.

DESCRIPTION

FIG. 1 is a perspective view of a sling with drawstring showing my new design, with the drawstring actuated;

FIG. 2 is a right side elevational view thereof with drawstring not actuated;

FIG. 3 is a left side elevational view thereof;

FIG. 4 is a front elevational view thereof;

FIG. 5 is a rear elevational view thereof;

FIG. 6 is a perspective view thereof;

FIG. 7 is a top view thereof; and,

FIG. 8 is a bottom view thereof.

The broken lines illustrating a person in FIG. 1 shows environmental structure and form no part of the claimed design.

It is understood that the broken lines within the claimed design indicates stitching, which form part of the claim.
